UNITED STATES PATENT OFFICE.

CALVIN C. WOOLWORTH, OF NEW YORK, N. Y.

IMPROVEMENT IN ENVELOPES.

Specification forming part of Letters Patent No. 41,804, dated March 1, 1864.

To all whom it may concern:

Be it known that I, CALVIN C. WOOLWORTH, of 66 John street, in the city, county, and State of New York, have invented a certain new and useful Improvement in Envelopes; and I do hereby declare the following to be a full and exact description of the same, reference being had to the accompanying drawings, making part of this specification, in which—

Figures 1 and 2 are perspective views of my improved envelope, showing the flaps in different positions. Fig. 3 represents the same as buckled or tied up after being filled with a number of letters for transportation. Fig. 4 is a side view.

Similar letters of reference indicate corresponding parts in the several views.

This invention relates to an envelope for the use of post-offices, express companies, mercantile houses, &c., designed principally to economize time and material in wrapping or inclosing letters or other matters for transmission between certain points for which the envelopes may have been expressly prepared.

In order that others skilled in the art to which my invention appertains may be enabled to fully understand and use the same, I will proceed to describe it and the manner of carrying it into effect.

In the accompanying drawings, A A' represent the sides of the pocket or receptacle, which may be connected together at each end by a gusset, B.

C' represent flaps, each of which is formed in one piece, with the respective side pieces, A A', of the pocket constituting extensions thereof, which it is designed to make of equal dimensions.

This envelope may be made of leather, parchment, paper, or paper and linen combined, or of any other material of sufficient strength, durableness, and flexibility to adapt it to contain a number of letters or other matters to be transmitted from one place to another, and then have its contents removed, be refilled, and returned, and be thus employed a number of times, in the manner to be described.

The description of my invention will be elucidated by reference to the printing on the specimen exhibited in the accompanying drawings. This specimen is supposed to be employed for containing letters or other mail-matter to be conveyed from the post-office at Chicago, Illinois, to the post-office at St. Joseph, Missouri, and then returned with letters, &c., for the post-office from which it was first sent. Upon the outside of the piece A of the pocket, and also upon the outside of the flap C, the name of the former place is printed or stamped, the letters upon the piece A being placed in anti-position with or reversely to those upon the flap C, so that when the said flap is turned over or down upon the opposite side the destination of the parcel may be easily read from either side of the envelope. In like manner the name of the last-named place is printed upon the piece A' and its flap C'. When the envelope, with its contents, is to be mailed to the post-office at St. Joseph, the flap upon which the name of the place from which it is sent is printed or stamped is turned down within the pocket, and the flap bearing the name of its destination turned over the mouth of the pocket and down upon the opposite side and over the name of the place from which it is sent, in which position it may be secured by a strap, D, or otherwise. The contents of the envelope having been removed at St. Joseph, and replaced by matters for the post-office at Chicago, the envelope may be readily adapted for mailing to the latter place by merely withdrawing the flap C from the pocket, inserting therein the flap C', and turning and securing the flap C over the inscription on the side A' of the pocket.

Though chiefly designed for the use of post-offices, this envelope may be employed to advantage by express companies and for other purposes.

By this invention not only may the time required in directing be reserved for other purposes, but the article is rendered almost invaluable by the great saving of material effected by its use.

I am aware that an envelope resembling mine in its general construction is described

in a patent granted to H. C. Bristol on the 27th of January, 1863, and therefore I do not claim, broadly, the particular form of the envelope.

Having thus described my invention, the following is what I claim as new therein, and desire to secure by Letters Patent:

The use of an envelope of the construction described, with different addresses applied to its respective flaps or sides, or both, so that by reversing the positions of the flaps the en-

velope will be adapted for transmission in alternate directions between certain places, all as hereinbefore explained.

The above specification of my improvement in envelopes signed this 16th day of October, 1863.

CALVIN C. WOOLWORTH.
